CHARLES G. BAUER, OF BROOKLYN, NEW YORK, ASSIGNOR, BY MESNE ASSIGNMENTS,
TO CHARLES G. BAUER AND EDWIN L. GARVIN.

MACHINE FOR USE IN THE MANUFACTURE OF TEXTILE FABRICS.

Application filed May 7, 1923. Serial No. 637,119.

My invention relates to machines for use in the manufacture of textile fabrics, and while the embodiment of the invention herein specifically described is a loom for weaving tubular fabrics, it will be understood that certain principles of the invention are applicable to various other machines of this general class.

An object of the invention is to improve the construction and mode of operation of machines of the character indicated as will hereinafter appear.

A more specific object of the invention is to provide in a machine of this character an arrangement of electro-magnets or other magnetically operated devices for effecting the laying or crossing of the threads or strands in forming a woven or other textile fabric, whereby the use of complicated mechanisms for this purpose may be eliminated.

Another object of the invention is to provide a loom for weaving tubular fabric which is simpler in construction, and capable of operating at a higher speed and otherwise more efficient than those heretofore produced.

With these and other objects in view the features of the invention consist in certain constructions, arrangements and combinations of parts hereinafter described and claimed, the advantages of which will be obvious to those skilled in the art.

The several features of the invention will be clearly understood from the following description and accompanying drawings, in which,—

Figure 1 is a front elevation of a wire covering machine embodying the features of my invention in their preferred form;

Fig. 2 is a right side elevation of the same;

Fig. 3 is a sectional view taken on the line 3—3 of Fig. 2;

Fig. 4 is a sectional elevation taken on the line 4—4 of Fig. 1;

Fig. 5 is a detail longitudinally sectional view on an enlarged scale, partly in elevation, of two opposed electro-magnets and associated parts with a bobbin arranged between them forming component parts of the machine, the outer portion of one of the electro-magnets being broken away;

Fig. 6 is a detail sectional view on an enlarged scale of a portion of the machine illustrated in Fig. 3;

Fig. 7 is a view similar to Fig. 6 but show-

ing this portion of the machine set up to form a tubular fabric;

Fig. 8 is a front elevation, partly in section, of a commutator that is employed on the machine;

Fig. 9 is a sectional view taken on the line 9—9 of Fig. 8; and

Fig. 10 is a diagrammatical view of the electrical connections of the machine.

The frame of the machine illustrated in the drawings is provided with a base plate 2 and side frames 4 having their lower ends secured to the base plate and their upper ends rigidly connected by a tie-rod 6. The side frames 4 are provided with hubs 7 having central apertures in which are secured by set screws 9 the outer ends of two tubular supporting members 8 and 10, respectively, which are arranged in axial alinement with their inner ends spaced a distance apart.

The illustrated machine is particularly adapted for use in covering wire. When the machine is used for this purpose the wire is fed axially through the tubular supporting members 8 and 10 in the direction of the arrow shown in Fig. 3. The wire which is indicated at 12 is guided in the tubular member 8 by means of a guide sleeve 14 secured in the inner end of said member by means of a set screw 16. The wire is guided in the tubular member 10 by means of a guide sleeve 18 that is secured in the inner end of the member by means of a set screw 20. The guide sleeves 14 and 18 project toward each other beyond the inner ends of the tubular members 8 and 10 and their inner ends are positioned in close proximity and are bevelled outwardly. When the machine is set up as shown, it is adapted to weave a covering on the wire consisting of twenty-four longitudinal strands 21, and four cross strands 23, the latter being laid or woven simultaneously. The longitudinal strands 21 are drawn from bobbins 22 which are arranged circumferentially about the inner ends of the guide sleeves 14 and 18 with their axes parallel to the axis of the guide sleeves and equally spaced apart, and the four cross strands 23 are drawn from cops 24 through thread guides 26 which are so positioned as to guide the stretches of the strands extending from the guides to the wire, in a common plane perpendicular to the axis of said sleeves and adjacent the inner end of the guide sleeve 18. During the operation of the machine, the thread guides 26 are simultaneously

carried concentrically about the axis of said guide sleeves, and the bobbins are shifted axially in opposite directions a distance greater than their width in proper timed relation to each other and to the operation of the thread guides 26 to effect the weaving of the covering on the wire, each bobbin being so supported as to enable the cross strands to be carried across either side thereof depending upon the position to which it is moved. The weaving of the strands on the wire takes place adjacent the inner end of the sleeve 18, this sleeve serving as a condenser for the strands.

The bobbins 22 are each mounted for rotation on and to slide from one to the other of heads 28 that are formed on pins 30 of brass or other non-magnetic material, the pins being arranged in axial alignment and with the inner ends of their heads 28 spaced a distance from opposite sides of the plane of the stretches of the strands extending from the guides 26 to the wire. Each bobbin is adapted to be thus shifted from one to the other of the heads 28 by means of two electromagnets 32 surrounding the pins 30 and arranged at opposite sides of the bobbin. Each magnet 32 is provided with a central core 34 having its outer end reduced in diameter and secured in an aperture in the end of an arm 36, and the coil 37 of the magnet is held on the core 34 between annular disks 38 of fibre or other insulating material, the inner disk 38 being arranged adjacent a flange 40 formed on the inner end of the core, and the outer disk being arranged adjacent the arm 36. The pins 30 are mounted in axial apertures in the magnet cores 34. The flanges of each bobbin 22 are each made in two concentric sections arranged one within the other, the inner section 42 being formed integral with the core of the bobbin and this section and the core being made of magnetic material, and the outer section 44 being made of fibre or other non-magnetic material and being secured to the inner section by means of screws 46. With this construction it will be apparent that when one of the magnets of each pair is energized and the other magnet is de-energized, the bobbin will be drawn toward the energized magnet so as to bring it a distance to one side of the plane of the stretches of strands extending from the thread guides 26 to the wire, and vice versa. In order to insure the immediate disengagement of the bobbin from a magnet when the magnet is de-energized and the other magnet is energized and to maintain the bobbin under control at all times during its movement from one to the other magnet, a sleeve 48 of brass or other non-magnetic material is mounted to slide on each pin 30, the inner end of the sleeve being provided with a flange 49 that normally is substantially in the plane of the inner end of the associated head 28. The sleeve 48 is urged

toward the end of the pin by means of a spring 50 coiled about the pin and interposed between the outer end of the sleeve and a shoulder 52 formed on the wall of the axial aperture of the associated core of the magnet. 70 this movement of the sleeve being limited by the engagement of a stop shoulder 54 thereon with the outer end of the head 28. With this construction when one of the magnets is energized, the bobbin on being pulled toward the magnet will engage and force back the sleeve 48 associated with the magnet until the flange of the sleeve is brought against the end of the core of the magnet, and when this magnet is de-energized and the other magnet is 80 energized, the spring 50 which was placed under tension by this retracting movement of the sleeve will be permitted to act immediately to force the bobbin away from the de-energized magnet and in the direction of pull 85 of the energized magnet, thus cooperating with the energized magnet to shift the bobbin. As the normal position of the sleeve is such that its flange is substantially in the plane of the end of the supporting head 28, the sleeve 90 will continue to follow up the bobbin until and after the bobbin engages the sleeve associated with the energized magnet, the bobbin forcing back the latter sleeve and tensioning its spring so as to enable it to act immediately when the latter magnet is de-energized.

The construction of the outer section 22 of the flanges of each bobbin of non-magnetic material reduces the danger of the magnetic flux developing in one bobbin from interfering with the other bobbins. To enable the bobbins to be easily removed and replaced the pins 30 are adapted to be retracted against the tension of the springs 50, a knob 56 being secured to the outer end of each pin which by engagement with the outer end of the magnet core, limits the inward movement of the pin.

The bracket arms 36 on which the left-hand series of magnets are mounted are formed on a bracket member 58 which is secured on the inner end of the tubular member 8 by means of a set screw 60 screw-threaded through an inwardly projecting hub on the member, the arms 36 projecting radially. The bracket 110 arms 36 on which the right-hand series of magnets are mounted are formed on a bracket member 62 which is secured on the inner end of the tubular supporting member 10 by means of a set screw 64 which is screw-threaded through an aperture in an inwardly projecting hub 66 formed on said member.

The strand guides 26 are formed on the ends of horizontal portions 68 of arms 70 that project radially from and are secured at their lower ends to a flange 72 formed on the inner end of a rotating carrier sleeve 74 which is mounted for rotation on the tubular member 8 between the left-hand side frame 4 and the bracket member 58, the arms 70 being equally 130

spaced about the axis of the sleeve 74. The thread cops 24 are mounted on suitable brackets 76 secured to the flange 72, the strands passing from the cops through eyelets 78 secured to the upper end of the vertical portion of the carrier arms 68 and over the horizontal portion of the arms to the thread guides. The carrier sleeve 74 is adapted to be driven through pulleys 80 mounted thereon.

10 The operation of the magnets is controlled by a commutator which is provided with a drum 82 carried by a horizontal shaft 84 having its ends journaled in bearings in the side frames 4. The shaft 84 is driven from the 15 carrier sleeve 74 by means of a sprocket chain 86 that passes over sprocket wheels 88 and 90 secured on the sleeve and shaft, respectively.

20 The commutator drum 82 is made up of six segments 92, the hubs of which are arranged 25 end to end on a metallic sleeve 94 having a collar 96 secured on one end thereof by a set screw 97, and a clamping nut 98 screw-threaded on the other end thereof for clamping the hubs of the segments 92 in position 30 on the sleeve. A commutator-ring 100 is also clamped on the sleeve 94 between the nut 98 and the right-hand end segment 92. The sleeve 94 is insulated from the shaft 84 by means of a sleeve 102 of insulating material secured to the shaft. The commutator is further provided with two sets of brushes 104 and 106 which are arranged diametrically opposite to each other, each segment 92 being adapted to engage one brush of each set.

35 Each brush 104 is pivotally and electrically connected at 108 to a metal strip 110 secured to a block of insulating material 112 mounted on the base plate 2. The brushes are pressed toward the commutator drum by means of a 40 spring 114 coiled about a screw 116 that extends through an enlarged aperture in the brush and is mounted in an aperture in the block 112, the spring being interposed between a nut 118 screw-threaded on the upper end of 45 the screw and a washer 120 engaging the top surface of the brush. Each brush 106 is pivotally and electrically connected at 122 with a metal strip 124 which is secured to a block of insulating material 126 mounted on the base 50 plate 2. The brush 106 is urged toward the commutator drum by means of a spring 128 which is coiled about a screw 130 mounted to slide through an aperture in the block 126 and extends loosely through an aperture in the 55 brush, the screw being provided with a head 132 that engages the under side of the brush and the spring 128 being interposed between a nut 134 screw-threaded on the upper end of the screw and a washer 136 engaging the block 60 126.

65 Each brush 104 is electrically connected by a wire 138 in series with the coils 32 of a set of four equally spaced magnets of one series of magnets (Fig. 10), and each brush 106 is similarly connected by a wire 140 with the coils

of a set of four equally spaced magnets of the other series, so that the magnets of each pair are connected to the two brushes of a segment, respectively. The coils of all the magnets are connected in series through a battery 142, or other source of electric supply, with a brush 144 engaging the collector-ring 100, the brush 144 being mounted similarly to the brushes 106. The commutator segments 92 are equally and progressively spaced about the shaft 84, as shown in Figs. 8 and 9 and are of suitable length so that as a brush 104 is engaged by one of them it is carried out of contact with its other brush 106.

70 With this construction it will be apparent 80 that the pairs of electromagnets will be correspondingly operated in sets of four, a corresponding magnet of each pair being energized while the other magnet is de-energized, and that the pairs of magnets between each such set of four will be successively operated correspondingly. As the commutator shaft makes two revolutions to one of the carrier sleeves 74 it will be apparent that the four 85 equally spaced thread guides 26 will operate in such timed relation to the operation of the magnets, and hence to the shifting movements of the bobbins that during their rotation they will carry their strands simultaneously across the same sides of four bobbins, and then simultaneously across the opposite sides of the succeeding bobbins and so on, the four strands being thus simultaneously laid or interwoven with the bobbin strands 95 so as to effect a plain circular weave as the 100 wire is being fed.

105 The wiring for connecting the left-hand series of magnets with the commutator, may be passed through apertures 145 in the hub of the bracket member 58 and the tubular supporting member 8 and out through the tubular member, so as not to interfere with the rotating strand carrying arms 70; and the wiring for the right-hand series of magnets may be carried down to the commutator 110 in any suitable manner.

115 It will be apparent that the closeness of the weave may be varied by merely varying the speed of the feeding movement of the wire or fabric. To this end a feed mechanism is provided that has provision for adjustment by the operator to vary the speed thereof.

120 The feed mechanism comprises a feed wheel 146 over which the wire and its covering pass. The feed wheel is mounted on a shaft 148 which is journaled to rotate in suitable bearings formed on a bracket 150 secured by set screws 152 to the hub on the right-hand side frame 4. One face of the feed wheel 146 is in the form of a friction disk and is engaged by a friction driving pinion 154 secured by a set screw 156 on a shaft 158 having its ends journaled in suitable bearings in a yoke 159 formed on the bracket 150. The shaft 158 is 125 130

driven by a ratchet wheel 160 secured on one end thereof which is engaged by an operating pawl 162 mounted on an arm 164 having one end pivotally mounted on the shaft 158 and its other end connected by a link 166 with a crank disk 168 secured on the right-hand end of the commutator shaft 84. By adjusting the position of the driving pinion 154 longitudinally of the shaft 158 the speed of rotation of the feed wheel 146 may be varied as desired. It has been found that the intermittent movement imparted to the feed wheel 146 by the ratchet wheel 160 is preferable in some cases to a more continuous feed.

15 It will be apparent that the machine may be used in covering wire of different sizes by merely employing guide sleeves 14 and 18 of the proper sizes.

When it is desired to weave a tubular fabric without weaving it on a wire, a forming mandrel 170 may be used which is provided with a tapering end 172 extending into the inner end of the guide sleeve 18, the tool being held in a tool-holder in the form of a sleeve 174 which is secured in the inner end of the tubular member 8 by means of the set screw 16, the inner end of the tool-holder being bevelled outwardly the same as the end of the guide sleeve 14. When the mandrel 170 is used the fabric is woven about the tapering end 172 of the mandrel adjacent the end of the guide sleeve or condenser 18, and as it is woven it slips off of the end of the tool as the fabric is fed, the feeding of the fabric being accomplished by the feed wheel 146.

It has been found that it is only necessary to draw the bobbin strands through the guiding member or condenser 18 to the feeding device, and insert the ends of the longitudinal strands into the end of the condenser, in order for the weaving operation to properly take place when the machine is started.

While the features described above are well adapted for use in a wire covering machine or circular loom, it is to be understood that, except as defined in the claims, certain features of the invention are not limited to a machine of this character as they may be employed in looms of various types and in braiding machines.

What I claim is:

1. A machine for use in the manufacture of textile fabrics having, in combination, a pair of electro-magnets arranged end to end and spaced apart, guide pins of non-magnetic material projecting from the inner ends of said magnets and having their inner ends spaced apart, and a strand carrier of magnetic material capable of sliding upon and from one to the other of said pins a distance greater than the width thereof.

2. A machine for use in the manufacture of textile fabrics having, in combination, a bobbin, means for supporting the bobbin comprising two members arranged end to end

and spaced apart upon which the bobbin is adapted to rotate and to be shifted axially in opposite directions from one to the other a distance greater than its width, and controllable means for thus shifting the bobbin comprising an electro-magnet surrounding one of said members for shifting the bobbin in at least one of said directions.

3. A machine for use in the manufacture of textile fabrics having, in combination, a pair of electro-magnets arranged end to end and spaced apart, guiding members of non-magnetic material projecting from the inner ends of said magnets arranged in axial alignment and having their inner ends spaced apart, a bobbin in part constructed of magnetic material capable of sliding upon and from one to the other of said guiding members a distance greater than its width, one of said guiding members being adapted to be retracted to permit removal of the bobbin.

4. A machine for use in the manufacture of textile fabrics having, in combination, a pair of electro-magnets arranged end to end and spaced apart, guide pins of non-magnetic material projecting from the inner ends of said magnets arranged in axial alignment and having their inner ends spaced apart, a bobbin in part constructed of magnetic material capable of sliding upon and from one to the other of said pins a distance greater than its width, sleeves of non-magnetic material mounted to slide on said pins, respectively, and springs for urging said sleeves toward each other, each sleeve tending to slide the bobbin in a direction away from the magnet associated with the sleeve when said magnet is de-energized.

5. A machine for use in the manufacture of textile fabrics having, in combination, a bobbin mounted for axial movement in opposite directions, means comprising two electro-magnets arranged at opposite sides of said bobbin for alternately moving the bobbin axially in opposite directions, respectively, a distance greater than the width of the bobbin, and a mechanically operated device associated with each magnet acting to slide the bobbin in a direction away from said magnet when said magnet is de-energized.

6. A machine for use in the manufacture of textile fabrics having, in combination, a plurality of flanged bobbins arranged in proximity to each other with their axes parallel, each having its central portion made of magnetic material and the outer peripheral portion of its flanges of non-magnetic material, and means associated with each bobbin comprising two electro-magnets arranged at opposite sides of the bobbin for alternately moving the bobbin axially in opposite directions, respectively, a distance greater than the width of the bobbin.

7. A machine for use in the manufacture of textile fabrics having, in combination, a

- condenser, a series of bobbins each having a strand wound thereon arranged circumferentially about said condenser with their axes parallel with the axis of said condenser, a series of pairs of guiding members, the members of each pair being arranged end to end and spaced apart and each pair arranged to support a bobbin and to enable the bobbin to be slid from one to the other a distance greater than its width, means for drawing a strand from each of said bobbins and through said condenser, a strand carrier rotatable circumferentially about said condenser outside of said bobbins for guiding a strand to said condenser, means for thus rotating said carrier, and means comprising electro-magnets arranged at opposite sides of each bobbin for alternately sliding said bobbins successively in opposite directions a distance greater than their width so as to enable the strand carried by the strand carrier to be passed successively between the ends of said guiding members of each pair and alternately across opposite sides of said bobbins.
8. A machine for use in the manufacture of textile fabrics having, in combination, a tubular member constituting a strand condenser, a series of pairs of electro-magnets arranged circumferentially about one end of said tubular member, the magnets of each pair being arranged in axial alinement and spaced apart and having their cores arranged parallel with said tubular member, a frame surrounding said tubular member having a series of radially projecting arms with each arm supporting one magnet of each pair, a second frame spaced from said end of said tubular member and having a series of radially projecting arms with each arm supporting the other magnet of each pair, a bobbin of magnetic material mounted to slide in opposite directions between the magnets of each pair a distance greater than its width so as to enable a strand to be passed across opposite sides of the bobbin, means for drawing a strand from each of the bobbins and through said end of said tubular member, a plurality of strand carriers for guiding strands to said end of said tubular member mounted for rotation about the axis of said tubular member and outside of said bobbins so that strands carried thereby will traverse a plane midway between the limits of movement of said bobbins, and controllable means for relatively energizing said magnets and for rotating said strand carriers in timed relation.
9. A machine for use in the manufacture of textile fabrics having, in combination, two tubular members arranged in axial alinement and spaced a sufficient distance apart to enable a strand to be passed between them, a series of pairs of electro-magnets, the magnets of each pair being arranged in axial alinement and spaced apart and having their cores arranged parallel with the axis of said tubular members, two frames surrounding said tubular members, respectively, and each having a series of radially projecting arms, each arm supporting one of the magnets of each pair, a bobbin mounted between the magnets of each pair and adapted to be moved axially in opposite directions a distance greater than its width upon the magnets associated therewith being energized, respectively, so as to enable a strand to be passed across opposite sides of the bobbin, a carrier rotatably mounted for rotation about one of said tubular members, means on said carrier for supporting a plurality of strand cops, a plurality of guiding members carried by said carrier for guiding strands from said cops in the plane midway between the limits of movement of said bobbins and into the end of one of said tubular members, means for drawing thread from said bobbins and through said end of said tubular member, and controllable means for relatively energizing said magnets and for rotating said carrier in timed relation.
10. A machine for use in the manufacture of textile fabrics having, in combination, a tubular member constituting a strand condenser, a series of pairs of electro-magnets arranged about the condenser with their axes parallel with the axis of the condenser and with the magnets of each pair arranged end to end and spaced apart, means for supporting a bobbin between the magnets of each pair in such a manner as to enable the bobbin to be axially shifted a distance greater than its width so as to enable a strand to be passed across opposite sides of the bobbin, shifting of the bobbin in opposite directions being effected by means of the magnets, respectively, means for drawing strands from the bobbins and through the condenser, a strand carrier for guiding a strand to the condenser and rotatable about the condenser outside of the bobbins so as to cause the strand to be varied in a plane midway between the limits of movement of the bobbins, and controllable means for relatively energizing the magnets and rotating said carrier in timed relation.
11. A machine for covering wire having, in combination, two tubular members arranged in axial alinement with their inner ends spaced apart, means for feeding a wire through said tubular members, supporting frames surrounding each of said tubular members, and each having a series of radially extending arms with the arms of the two series oppositely arranged, respectively, an electro-magnet mounted on each of said arms, the magnets on the two supporting members being arranged end to end and spaced apart so as to provide a series of pairs of magnets, a guiding member on the inner end of each magnet, the guiding members of each

- pair of magnets being arranged end to end and spaced apart, a bobbin arranged between the magnets of each pair and mounted to slide on the guiding members associated with 5 the magnets from one to the other a distance greater than its width, a carrier rotatably mounted for rotation about one of said tubular members, means thereon for supporting a plurality of thread cops, means comprising 10 arms projecting from said carrier for guiding thread from the cops to said wire at a point between the ends of said tubular members, the stretches of the strands extending from the arms to the wire being arranged in 15 a plane midway between the ends of said bobbin guiding members, and controllable means for relatively energizing said magnets and for rotating said carrier in timed relation.
12. A machine for use in the manufacture of textile fabrics having, in combination, a series of pairs of electro-magnets with the magnets of each pair arranged end to end and spaced apart, means for supporting a bobbin between the magnets of each pair so as to enable the bobbin to be rotated and to be shifted axially in opposite directions a distance greater than its width to enable a strand to be passed across opposite sides of the bobbin, means for drawing strands from the bobbins in the same general direction, and means for laterally traversing a strand successively across the sides of the bobbins in a plane midway between the limits of the shifting movements of said bobbins, and controllable means for relatively energizing the magnets and for operating said strand traversing means in timed relation.
13. A machine for use in the manufacture of textile fabrics having, in combination, a bobbin mounted for axial movement horizontally in opposite directions, and controllable means comprising two electro-magnets arranged at opposite sides of said bobbin for 45 moving the bobbin in said directions.
14. A machine for use in the manufacture of textile fabrics having, in combination, two guide pins arranged horizontally in axial alignment and having their inner ends spaced 50 a distance apart, a bobbin of greater width than the distance between the ends of said pins, and means comprising electro-magnets surrounding said pins for shifting the bobbin from one to the other of said pins to positions at opposite sides of a plane extending centrally between the ends of said pins. 55
15. A circular loom having, in combination, a bobbin mounted for axial movement in opposite directions, means comprising an electro-magnet arranged at one side of said bobbin for moving the bobbin axially in one direction a distance greater than its width, and a mechanically operated device associated with said magnet and acting to shift the bobbin in the opposite direction when 60 said magnet is deenergized. 65
16. A circular loom having, in combination, a rotatable bobbin mounted for axial movement in opposite directions, means comprising electro-magnets acting directly on the bobbin for shifting it axially in opposite directions, and mechanically operated devices tending to shift the bobbin to a position substantially midway between its limits of movement when said electro-magnets are deenergized. 70
17. A circular loom having, in combination, a rotatable bobbin mounted for axial movement in opposite directions, means comprising electro-magnets acting directly on the bobbin for shifting it axially in opposite directions, and mechanically operated devices each cooperating with one of said magnets to shift the bobbin in one direction when said magnet is energized. 75
18. A circular loom having, in combination, a rotatable bobbin, means for positively guiding and supporting the bobbin comprising members arranged end to end and spaced apart upon which the bobbin is adapted to be shifted axially from one to the other a distance greater than its width, each of said members alone being adapted to support said bobbin for rotary movement, and controllable means for thus shifting the bobbin comprising electro-magnets arranged to act directly on the sides, respectively, of the bobbin. 80
19. A machine for use in the manufacture of textile fabrics having, in combination, a bobbin mounted for movement in opposite directions, resilient means tending to move the bobbin in one direction, and means comprising an electro-magnet for moving the bobbin in the opposite direction against the action of said resilient means. 100

CHARLES G. BAUER.
